AIR COOLING AND CIRCULATING DEVICE

Willard L. Morrison, Lake Forest, Ill.

Application August 16, 1938, Serial No. 225,178

5 Claims. (Cl. 62—140)

This invention relates to an air cooling and circulating device and has for its object to provide a new and improved device of this description.

The invention has as a further object to provide an air cooling and circulating device particularly adapted for cooling rooms.

The invention has as a further object to provide an air cooling and circulating device which may be placed in a room and which may be utilized to cool without drafts only the lower part of the room.

The invention has as a further object to provide an air cooling and circulating device in the form of a cabinet which may be placed in a room and which is provided with cooling apparatus which may be operated in such a manner as to store up cold in the cabinet, which cold may be liberated when desired so that the device is ready to operate to at once cool the room when the cooling is desired.

The invention has further objects which are more particularly pointed out in the accompanying description.

Referring now to the drawings:

Fig. 1 is a plan view of one form of the device embodying the invention;

Fig. 2 is a sectional view taken on line 2—2 of Fig. 1;

Fig. 3 is a sectional view taken on line 3—3 of Fig. 2;

Fig. 4 is a sectional view taken on line 4—4 of Fig. 2;

Fig. 5 is a sectional view taken on line 5—5 of Fig. 2 with parts omitted;

Fig. 6 is a vertical sectional view through the upper portion of the cabinet;

Fig. 7 is a view showing the device in a room;

Fig. 8 is a view as seen from line 8—8 of Fig. 7;

Fig. 9 is a view similar to Fig. 6 showing a modified construction.

Like numerals refer to like parts throughout the several figures.

Referring now to the drawings wherein I have illustrated certain forms embodying the invention, there is provided a cabinet 1 which is preferably a movable cabinet preferably mounted on wheels 2 so that it may be easily and quickly moved about the room. In the lower part of the cabinet I preferably provide a compressor 3 operated by a motor 4. There is a condenser 5 which is preferably located at the top of the cabinet as shown. This condenser is connected by a pipe 6 to the compressor through which the liquid from the compressor passes to the

condenser. There is a pipe 7 which leads from the condenser back to the receiver 8 and conducts the cooled liquid from the condenser back to said receiver. This liquid is then passed through the expansion valve 9 and thence by pipe 10 through the coil 11 and thence back by pipe 12 to the condenser.

The coil 11 is located in a tank 13 which contains a refrigerant material such as brine or the like which may be given a low temperature without freezing. This refrigerant material, cryohydrate, may therefore be used to store cold and may be brought to a low temperature. The cryohydrate, when the device is used for cooling a room, is passed through a cooling coil 14 with which air comes into contact, which air then drops into the room to cool the lower part thereof. The cryohydrate is passed through the cooling coil 14 in any desired manner. As here shown, there is provided a pump 15 which is driven in any manner by a shaft 16 from the motor 4. This pump pumps the cryohydrate up through the pipe 17 and the cooling coil 14, and thence through the pipe 18 back into the tank 13. There is preferably provided a controlling device which consists of the bulb 19 and which controls the admission of the refrigerant to the evaporator coil 11 by controlling the expansion valve 9, or in any other suitable manner.

There is a passageway 20 in the cabinet leading from the upper part thereof to the chamber 21 in which the motor and compressor are located. There is another passage 22 connecting with this chamber 21. The arrangement is such that air from the upper part of the room passes down into the chamber 21 to cool this chamber and the compressor and motor and then passes up through the passageway 22 to the upper part of the room. I prefer to arrange the passageway 20 so that its discharge end into the chamber 21 is below the lower or admission end of the passageway 22 so as to facilitate the natural movement of the air down through the passageway 20 and up through the passageway 22. This construction is illustrated in Fig. 2, where the lower end 20a of the passageway 20 is below the lower end 22a of the passageway 22.

The condenser 5 is preferably uncovered, that is, the cabinet at this point is open at the top, and there are one or more passageways 23 through which air from the upper part of the room passes, this air coming into contact with the condenser so as to cool it and then passing up into the upper part of the room. The condenser is separated from the evaporator by a

partition 24 which is preferably of heat insulated material. There are one or more openings 25 in the cabinet through which air passes to the cooling coil 14. This air is cooled by this evaporator and then passes out through one of the openings 26 and is dropped by gravity to the bottom of the room to be cooled. There is an inclined member 27 below the cooling coil for catching the water of condensation produced by the cooling coil. This water is conducted by the means of a pipe 28 to a tank 29 located in the cabinet. Some means are provided for closing off the cooling coil 14 to prevent the cold air from dropping into the room to be cooled. This may be done in any desired manner as by means of a door 30, which may be moved down into a recess 31 in the cabinet when it is desired to open it so as to permit cold air to pass out into the room.

In Fig. 9 I have shown a modified construction wherein the evaporator 32 is located near the top of the cabinet but is in a compartment 33 which is closed on all sides but is open at the top. The air to be cooled is conducted through one or more openings 34 to the evaporator by means of a hood or similar device 35. There is an air moving device 36 located above the evaporator which moves air through the evaporator down into the compartment 33. The air moving device is so arranged that it does not force the cold air out of the compartment 33 but simply moves it down into this compartment, and when the compartment fills up to the edge 37, the cold air then spills over the edge and passes out through the opening or openings 38 and drops by gravity into the lower part of the room so that there will be no current produced by the air moving device 36. This cold air, dropping by gravity into the lower part of the room, causes the warmer air in the lower part of the room to rise by thermosyphonic action, forming a zone of cool or conditioned air below the top of the cabinet in the same way as this zone is formed by the construction shown in Figs. 1 and 2.

It will be seen that by means of this device there is provided a cabinet containing a compressor, a condenser and an evaporator, and a cold storage tank or receptacle which provides a large supply of cold refrigerant or eutectic which can be passed through a cooling coil in the top of the cabinet. It will further be seen that there is provided here means for storing cold or cooled air so that it can be released or liberated at a point above the floor of the room when it is desired to cool the lower part of the room, and when so liberated, it drops by gravity into this lower part of the room, this cold air causing the warmer air in the lower part of the room to rise by thermosyphonic action. There is also means for causing the heat from the condenser to rise to the upper part of the room. By means of this device, only a part of the room is cool, that is, the lower part in which the human beings are located, and since there are no drafts, that is since the movement of the air is by thermosyphonic action, the warmth of the human beings and the warm breath breathed by them rises up by thermosyphonic action without being distributed or mixed with the cold air so that the cold air in the bottom of the room is maintained in a pure state for breathing purposes.

It will further be seen that the room is thus divided into two sections, an upper section and a lower section, the lower section being filled with cool air, the upper section being filled with warm

air, there being a stratification of these two sections so that the warm air in the upper section does not mix with the cold air in the lower section. Furthermore, it is unnecessary to have the walls of the room made of heat insulating material, because the heat which may be in or come through the walls can not get into the cold lower part of the room because it will automatically rise up and pass along the wall and enter the warmer upper section or stratification of air in the room. By this means, the efficiency of the cooling device is greatly increased as the cooling only takes place in the lower part of the room. Furthermore, since the room is stratified, that is, has an upper strata of warm air and a lower strata of cold air, the only air that is cooled is the air in the lower part of the room, and the heat from the breath of the human beings and from their bodies is not cooled but rises up to the upper strata of warm air. Because of this fact, and because of the fact that the warmth from the walls of the room does not enter this strata of cool air, this strata of cold air when once produced can be maintained in a cooled condition with very little effort and in a very efficient manner and at very little cost. Furthermore, since the device is run by an electric motor which may be connected with the ordinary outlet in the room, this permits a small motor to be used which will come within the requirements of the electric company so that no additional wiring is necessary.

When this device is in use to cool a room, the window is preferably open at the top, as shown at 39, Figs. 7 and 8, so that the warm air produced by the condenser and the human beings in the lower part of the room which rises up to the top of the room can freely pass out of the open window.

The use and operation of my invention are as follows:

When the cabinet is placed in a room, as shown for example in Figs. 7 and 8, the refrigerating apparatus may be operated at times when the device is not being used to cool the room so as to lower the temperature of the liquid in the tank 13 without this cool liquid being used to cool the room. Under these conditions, the door 30 will be moved up so as to close the openings 25 and 26. This operation, for example, might well take place at night when the cost of current is small. It can of course take place at any suitable time. If the device is used in an office, for example, it could be operated at night to cool this liquid in the tank 13, or it could be started up in the morning so as to be ready to cool the room when the occupants reach the office.

When it is desired to cool the room, the door 30 is then moved down in the position shown in Fig. 3 so as to open the openings 25 and 26. The cold air in the evaporator compartment 14a then drops down into the lower part of the room. This immediately provides a source of very cold air which at once drops into the bottom of the compartment. The liquid which is being passed through the evaporator and which has become very cold by the previous operation of the refrigerating apparatus, then quickly cools the air passing into the cabinet through the openings 25 and causes this cold air to drop by gravity through the openings 26 into the lower part of the compartment. The air which passes down through the passageway 20 is warmed by the compressor and motor and then passes up

through the passageway 22 into the upper part of the room. The air from the condenser 5 rises upwards.

I claim:

1. An air cooling and circulating device comprising a movable cabinet, a compressor in said cabinet, a tank in said cabinet containing refrigerant material, an evaporator immersed in said refrigerant material and operatively connected with said compressor, a cooling coil in the upper part of said cabinet, a connection between said cooling coil and said tank for circulating said refrigerant material through said cooling coil, said cabinet being provided with an opening through which cold air from said cooling coil is discharged into the lower part of the room, a movable closure for said opening which may be closed to hold the cold air in said cabinet and permit the temperature of the refrigerant in said tank to be brought to a low degree to store cold in the cabinet, the closure being opened when it is desired to cool the room, the cold air then dropping by gravity into the lower part of the room to quickly cool the lower part of the room, said cooled air causing the warmer air in the lower part of the room to rise by thermosyphonic action and forming a zone of conditioned air below the top of the cabinet, said device forming a unitary structure which may be moved to any part of a room.

2. An air cooling and circulating device comprising a cabinet, a compressor in said cabinet, a condenser at the top of said cabinet, thermosyphonic means for bringing air from the upper part of the room into contact with said condenser to cool it and discharge said air into the upper part of the room, a tank in said cabinet containing refrigerant material, an evaporator immersed in said refrigerant material and operatively connected with said compressor, a cooling coil in the upper part of said cabinet and below said condenser, a connection between said cooling coil and said tank for circulating said refrigerant material through said cooling coil, said cabinet being provided with an opening below said condenser through which cold air from said cooling coil is discharged into the lower part of the room, a movable closure for said opening which may be closed to hold the cold air in said cabinet and permit the temperature of the refrigerant in said tank to be brought to a low degree to store cold in the cabinet, cold air dropping by gravity into the lower part of the room to quickly cool said lower part when the closure is opened, said cooled air causing the warmer air in the

lower part of the room to rise by thermosyphonic action and forming a zone of conditioned air below the top of the cabinet.

3. An air cooling and circulating device comprising a cabinet, a compressor and condenser in said cabinet, a cooling coil in the upper part of said cabinet, an opening in the cabinet having its lower edge below the bottom of said cooling coil, through which air cooled by the cooling coil drops into the lower part of the room, a closure for said opening which holds the cold air in said cabinet and provides a cold air storage, said cold air when the closure is opened dropping by gravity into the lower part of the room to quickly cool it, said cold air causing the warmer air in the lower part of the room to rise by thermosyphonic action and forming a zone of cooled air below the top of the cabinet.

4. An air cooling and circulating device comprising a cabinet, a compressor and condenser in said cabinet, a cooling coil in the upper part of said cabinet, an opening in the cabinet through which air cooled by the cooling coil drops into the lower part of the room, a closure for said opening which holds the cold air in said cabinet and provides a cold air storage, said cold air when the closure is opened dropping by gravity into the lower part of the room to quickly cool it, said cold air causing the warmer air in the lower part of the room to rise by thermosyphonic action and forming a zone of cooled air below the top of the cabinet, and a storage compartment in said cabinet for storing the cold refrigerant supplied to said cooling coil.

5. An air cooling and circulating device comprising a cabinet, a compressor and condenser in said cabinet, a cooling coil in the upper part of said cabinet, an opening in the cabinet through which air cooled by the cooling coil drops into the lower part of the room, a closure for said opening which holds the cold air in said cabinet and provides a cold air storage, said cold air when the closure is opened dropping by gravity into the lower part of the room to quickly cool it, said cold air causing the warmer air in the lower part of the room to rise by thermosyphonic action and forming a zone of cooled air below the top of the cabinet, means inside of the cabinet for conducting the air heated by the compressor to the air in the upper part of the room without mixing with the cooled air in the cooled zone, and a storage compartment in said cabinet for storing the cold refrigerant supplied to said cooling coil.

WILLARD L. MORRISON.
